UNITED STATES PATENT OFFICE.

ALBERT SCHMIDT, OF FLINT, MICHIGAN, ASSIGNOR TO CHAMPION IGNITION COMPANY,
OF FLINT, MICHIGAN, A CORPORATION OF MICHIGAN.

SPARK-PLUG.

1,271,620.

Specification of Letters Patent.

Patented July 9, 1918.

Application filed April 27, 1917. Serial No. 164,842.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark-plugs, and has particular reference to a construction in which the insulated electrode is readily removable and which also provides compensation for the differential expansion of the 15 metal and the insulator.

In the drawings:

Figure 1 is a central longitudinal section through the spark-plug;

Fig. 2 is a cross section on line α — α 20 Fig. 1.

A is a metallic casing provided with the usual threaded nipple B for engagement with the engine casing, and C is the insulator secured within the casing, preferably by 25 providing a shoulder D and an opposed shoulder E, the metal of the casing being closed therearound while hot to form a gas-tight seal. F is an insulated electrode which passes through the central aperture 30 in the insulator, being inserted from the inner end thereof and having a shoulder G for bearing thereagainst. H is a clamping nut engaging the threaded outer end of the electrode to clamp the same to the insulator.

35 On account of the difference in coefficients of expansion of the insulating material and the metallic electrode, it is difficult to maintain a tight joint under varying conditions of temperature. To compensate for this, 40 instead of clamping directly against the outer end of the insulator the nut H bears upon a sleeve I which extends inward in a counterbore, thereby lessening the distance between the opposed points of bearing on 45 the insulator. There is, however, danger

that the shoulder against which the inner end of the sleeve bears may be overstrained, causing the cracking of the insulator. I have therefore provided a construction in which the sleeve I is threaded, as at J, and 50 this threaded portion is engaged with corresponding threads formed within the insulator. The number of bearings formed by successive convolutions of the thread are sufficient to distribute the stress from the 55 sleeve I into the body of the insulator C, thereby avoiding sharply-localized stresses and also avoiding danger of breaking. Furthermore, the threads form good heat-conducting contact between the insulator 60 and the sleeve, which assists in dissipating the heat of explosion.

If desired, the sleeve may be formed of material having a different coefficient of expansion from that of the electrode so as to 65 compensate for the differential coefficient of expansion of the insulator and metal.

What I claim as my invention is:

1. In a spark-plug, the combination with 70 an insulator, of an electrode extending therethrough, a metallic sleeve surrounding said electrode and having a different coefficient of expansion, said sleeve having a threaded engagement with the insulator, and clamping means for said electrode engaging the 75 outer end of said sleeve.

2. In a spark-plug, the combination with 80 an electrode, of an insulator through which said electrode passes, being formed with an inner portion for fitting the electrode and a portion having a bore of greater diameter 85 and internally threaded at its inner end, a sleeve or bushing surrounding said electrode correspondingly threaded and engaged with the threaded portion of the insulator, and clamping means upon said electrode for engaging the outer end of said sleeve or bushing.

In testimony whereof I affix my signature.
ALBERT SCHMIDT.
